F. M. HESS.
VAPOR BOX OR STILL FOR DISTILLATION SYSTEMS.
ORIGINAL FILED MAY 8, 1919.

UNITED STATES PATENT OFFICE.

FRANCIS M. HESS, OF WHITING, INDIANA.

VAPOR BOX OR STILL FOR DISTILLATION SYSTEMS.

Original application filed May 8, 1919, Serial No. 295,527. Divided and this application filed February 17, 1921. Serial No. 445,619.

To all whom it may concern:

Be it known that I, FRANCIS M. HESS, a citizen of the United States, residing at Whiting, in the county of Lake and State 5 of Indiana, have invented certain new and useful Improvements in Vapor Boxes or Stills for Distillation Systems, of which the following is a specification.

This invention relates to apparatus for 10 effecting the continuous distillation of hydrocarbon material such as coal tar and petroleum and their distillates; and has reference more particularly to an improved structure of vapor box or still adapted to the 15 use of superheated steam or any other gaseous heating agent as a heating medium.

The present application constitutes a division of an application heretofore filed by me on the 8th day of May, 1919, Serial 20 No. 295,527, method of and apparatus for effecting continuous distillation.

One object of the invention is to provide a vapor box or still wherein the material treated may flow in a broad thin stream 25 successively over a series of heated plates forming the walls of a zigzag conduit within the vapor box or still so as to be uniformly subjected to the heat of the heating medium flowing through said zigzag plates 30 which are made hollow for that purpose. Another object is to provide a construction of vapor box or still such that the entire structure may be easily disassembled for cleaning and repairs whenever necessary. 35 A further object is to provide a construction wherein the flow of the material through the vapor box or still shall be continuous and without interruption whereby to avoid carbon deposits in the bottom of the box.

40 A further object is to provide a construction of vapor box or still excellently adapted for use in a fractional distillation system employing a plurality of stills so grouped as to provide for a continuous gravity flow 45 of the material from the top member to the lower members of the series.

With these and other objects in view which will be apparent from the following detailed description, my invention consists 50 of the improved vapor box or still substantially as hereinafter described and illustrated in a practical form in the accompanying drawings, in which—

Fig. 1 is a vertical section through the 55 vapor box;

Fig. 2 is a horizontal section on the off-set line 2—2 of Fig. 1;

Fig. 3 is a detail front elevation partly in longitudinal vertical section, of the overflow trough of the vapor box; and

60

Fig. 4 shows a modified form of heating plate.

Referring to the drawing, the improved vapor box comprises an outer rectangular box-like housing or casing, consisting of 65 stationary top and bottom walls 5 and 6, stationary opposed side walls 7, and laterally removable opposed side walls 8 which are normally united to the side walls 7 by angle bars 9 and bolts 10. Within this 70 casing or housing is a zigzag conduit for the flow of the material to be distilled through the vapor box. This conduit is made up of hollow flat inclined plates or walls 11 and 12 that are connected at their 75 proximate ends by curved walls 11' and 12' respectively, of the same hollow formation. Each complete series of walls 11 and 12 is of zigzag or W-form, the two series being 80 internested, and the zigzag conduit for the flow of the material to be distilled being between them. These walls may be cellular castings as indicated in Fig. 2, or, as indicated in Fig. 4, they may consist of steel 85 plates 13 united at intervals by rivets 14 so as to provide a structure capable of resisting the maximum internal pressure of the superheated steam flowing therethrough.

The lower and upper walls 12 extend 90 through one of the side walls 8 and are coupled to supply and delivery connections 15 and 16, and the lower and upper walls 11 likewise extend through the opposite side wall 8 and are coupled to similarly supply 95 and delivery connections 17 and 18. Where a plurality of vapor boxes are connected up in series, the connections 15 and 17 will lead from the next lower vapor box, and connections 16 and 18 will lead to the next 100 higher vapor box of the group.

The walls 11 and 12 within the housing are supported on vertical frame structures 19 and 20, respectively, at each side, the two pairs of frames being connected by tie-rods 21 on which the inclined walls 11 and 12 rest, as clearly shown in Fig. 1. On the lower ends of the frames 19 and 20 are wheels 22 traveling on a pair of rails 23 forming a track-way. At one upper corner of the housing is an overflow trough 24 (Fig. 3) prefer- 110

ably formed with a serrated upper edge 24' on its front wall to distribute the material, into which trough the material is first introduced through a pipe 25 and from which it overflows onto the broad inclined top wall or plate 11 of the conduit, dropping from the end of the latter onto the topmost wall 27 flowing in a broad, wide stream down and off the lower end of the latter onto the next wall 11, and so on to the bottom of the vapor box; being discharged from the bottom wall 6 of the latter, through a pipe 26 into the next vapor box of the series, either directly, or, as shown in my former application hereabove referred to, through a residuum heated heat exchanger, or, in the case of the lowermost vapor box of the series, directly into a residuum tank or receiver. Superheated steam flows counter-current through these hollow walls, thereby rapidly and effectively heating the material and releasing the vapors as soon as the vaporizing temperatures of the latter are reached in the course of the material. Where a vertically arranged series of vapor boxes are employed in a fractional distillation system, the topmost vapor box is the coolest of the series and the lowermost vapor box is the hottest, so that the most easily formed vapors pass off from the topmost vapor box, while those forming at higher temperatures are discharged from the lower vapor boxes.

Whenever it becomes necessary to disassemble one of the vapor boxes, this is very easily done by removing one series of the bolts 10 at the corners of the structure so as to disconnect the side walls 8 from the side walls 7 and then drawing the side walls 8 with the conduit walls and their supports laterally apart on the track 23.

As hereinbefore stated the heating element preferably used herein is superheated steam. This affords a gaseous heating medium that is easy to regulate to any desirable temperature; it is also positive in its action; its temperature can be varied on short notice; it heats the liquid in all parts of the vapor box uniformly, and no hotter than desired; it can be operated at any desired pressure; and by running the superheated steam counter-current to the flow of the liquid through the vapor box the liquid is constantly increasing in temperature; and, in a multiple still system, by running the heating medium upwardly from vapor box to vapor box in a direction opposite to the flow of the liquid, the latter is heated in desirable successive steps.

The described construction of still or vapor box affords the following advantages. The material heated is kept constantly in motion and flows by its own gravity in a downward course from top to bottom of the vapor box, thus affording a constant pressure. In flowing in a broad thin stream

over the heating plates of the zigzag conduit it is most advantageously and uniformly subjected to the heat of the heating medium, and in falling from plate to plate it is successively atomized to release vapors. Since 70 the liquid flows entirely out of direct contact with the heating medium itself, there is no admixture of steam with the vapors given off by the material. There is ample space between the edges of the plates and the walls 75 of the casing or housing to allow the vapors to immediately rise and pass off through the vapor line, the vapors escaping from the vapor box through an outlet pipe 28 and passing thence to a suitable condenser. The 80 construction of the vapor box is such that the entire structure may be disassembled for repairs and cleaning when necessary with a minimum of time and labor. Furthermore, with the described construction, of vapor 85 box, and the material kept constantly in motion, the nuisance of carbon deposits in the bottom is eliminated. It is also noted that the described vapor-box or still is adapted to be operated with the vapors coming from 90 the vapor-box under the pressure caused by the gravity of the material; it may be operated with a partial vacuum in the vapor line; or it may be operated with a pressure greater than that caused by the gravity of 95 the material.

I claim:

1. In a distilling apparatus, a vapor-box comprising a casing having top and bottom openings for the introduction and discharge 100 respectively of the crude material and a series of alternately arranged oppositely inclined broad flat imperforate heating plates extending crosswise of said casing and providing a zigzag path of flow for the crude 105 material, said plates being hollow to permit the flow of a heating agent therethrough.

2. In a distilling apparatus, a vapor-box comprising a casing having top and bottom openings for the introduction and discharge 110 respectively of the crude material, and a continuous zigzag conduit for the flow of the crude material occupying approximately the full cross-sectional area of said casing, the walls of said conduit being hollow to permit 115 the flow of a heating agent therethrough.

3. In a distilling apparatus, a vapor-box comprising a casing having top and bottom openings for the introduction and discharge respectively of the crude material, and a continuous zigzag conduit formed with wide 120 flat imperforate top and bottom walls occupying approximately the full width of said casing, the said top and bottom walls of said conduit being hollow to permit the 125 flow of a heating agent therethrough.

4. In a distilling apparatus, a vapor-box comprising a casing having top and bottom openings for the introduction and discharge respectively of the crude material and a pair 130

of oppositely disposed removable side walls, and two groups of inclined broad flat heating plates attached to the removable sides of said casing and extending crosswise of the latter and together providing a zigzag path of flow for the crude material, said heating plates being hollow to permit the flow of a heating agent.

5. In a distilling apparatus, a vapor-box comprising a casing having top and bottom openings for the introduction and discharge respectively of the crude material and a pair 10 of oppositely disposed removable side walls,

two groups of inclined broad flat heating plates attached to the removable sides of said casing and extending crosswise of the latter and together providing a zigzag path of flow for the crude material, said heating plates being hollow to permit the flow of a heating agent therethrough, intermediate supports for said groups of heating plates, respectively, and a track-way on which said removable side walls and intermediate supports are mounted.

FRANCIS M. HESS.
